US00D944973S

(12) **United States Design Patent** (10) **Patent No.:** **US D944,973 S**
(45) **Date of Patent:** **** Mar. 1, 2022**

(54) **ORAL IRRIGATOR**

(71) Applicant: **Lei Yu**, Shenzhen (CN)

(72) Inventor: **Lei Yu**, Shenzhen (CN)

(73) Assignee: **Shenzhen Yuxinyuan Electronic Technology Co., Ltd.**, Shenzhen (CN)

(**) Term: **15 Years**

(21) Appl. No.: **29/731,564**

(22) Filed: **Apr. 16, 2020**

(51) LOC (13) Cl. **28-03**

(52) U.S. Cl.

USPC **D24/111**

(57) **CLAIM**

The ornamental design for an oral irrigator, as shown and described.

DESCRIPTION

FIG. 1 is a front, top perspective view of an oral irrigator showing my new design;

FIG. 2 is a rear, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the figures are for the purpose of illustrating portions of the oral irrigator, which form no parts of the claimed design.

1 Claim, 7 Drawing Sheets
